CLAIM

The ornamental design for a modular video support frame member, as shown and described.

DESCRIPTION

FIG. 1 is a front perspective view of a modular video support frame member showing our new design;

FIG. 2 is an enlarged front perspective view of a portion of the modular video support frame member shown in FIG. 1;

FIG. 3 is a front view the modular video support frame member;

FIG. 4 is a top view thereof, the bottom view is a mirror image of the top view;

FIG. 5 is a right-side view thereof, the left-side view is a mirror image of the right-side view; and,

FIG. 6 is a back view thereof.

The broken lines in the Figures are for the purpose of illustrating unclaimed portions of the modular video support frame member and form no part of the claimed design.
